[57] CLAIM

The ornamental design for a plastic safety cap for placement over the projecting sharp ends of concrete reinforcing bars, as shown.

DESCRIPTION

FIG. 1 is a view in side elevation of a plastic safety cap for placement over the projecting sharp ends of concrete reinforcing bars showing my new design.

FIG. 2 is a top plan view thereof.

FIG. 3 is a bottom plan view thereof.

FIGS. 4 and 5 are views in side and rear elevation, respectively, thereof and

FIG. 6 is a longitudinal sectional view of the safety cap showing concealed cross sectional contour which is part of my new design.
